MACHINE FOR FOLDING COMB HONEY SECTIONS AND APPLYING FOUNDATION
STARTERS THERETO

Application filed June 11, 1928. Serial No. 284,644.

This invention relates to a machine for manufacturing comb honey sections of that type provided with top and bottom starters of foundation combs.

5 The invention has for one of its objects to provide a machine of the character stated which shall be adapted to fold comb honey sections from blanks having dove-tail ends.

The invention has for a further object to 10 provide a machine of the character stated which shall be adapted to interlock or unite the ends of the folded blanks and thus complete the comb honey sections.

The invention has for a further object to 15 provide a machine of the character stated which shall be adapted to apply starters of foundation combs to the blanks in a manner to insure the starters occupying their proper positions in the completed comb honey sections.

20 The invention has for a further object to provide a machine of the character stated which shall be adapted to form the starters from blanks in rolled form and thereafter deliver and apply the starters to the comb honey section blanks.

The invention has for a still further object to 25 provide a machine of the character stated which may be operated manually or mechanically, which shall be adapted to deliver a comparatively large number of completed comb sections in a comparatively short time, and which shall be simple, durable and capable of being manufactured and sold at a comparatively low cost.

With the foregoing and other objects in view, the nature which will appear as the description proceeds, the invention consists in the construction, combination and arrangement of parts hereinafter fully described and claimed, and illustrated in the accompanying drawings, wherein:

Figure 1 is a view in front elevation of the machine,

45 Figure 2 is a view in side elevation of the machine.

Figure 3 is a sectional view on an enlarged scale taken on the plane indicated by the line 3—3 of Figure 2.

50 Figure 4 is a sectional view on an enlarged

scale taken on the vertical plane indicated by the line 4—4 of Figure 1.

Figure 5 is a sectional view taken on the vertical planes indicated by the line 5—5 of Figure 4.

55 Figure 6 is a sectional view on an enlarged scale taken on the vertical planes indicated by the line 6—6 of Figure 1,

Figure 7 is a sectional view taken on the plane indicated by the line 7—7 of Figure 6,

60 Figure 8 is a sectional view on an enlarged scale taken on the vertical plane indicated by the line 8—8 of Figure 1,

Figure 9 is a plan view on an enlarged scale of one of the members adapted to carry and apply the starters to the section blanks,

65 Figure 10 is a plan view of one of the section blanks, and

70 Figure 11 is an elevational view of one of the sections partly completed.

75 The machine comprises a frame which consists of base pieces 1, upright rear side bars 2, upwardly and rearwardly inclined front side bars 3 and lower and upper cross bars 4 and 5, respectively.

80 The magazine which comprises two receptacles 6 arranged in vertical position and in relatively spaced relation at the front side of the frame, is provided for the reception of the blanks 7 from which the honey comb sections are formed. The receptacles 6 are supported from the frame bars 3 by brackets 8 to which they are secured, as at 9. The upper ends and inner sides of the receptacles 6 are open, and the receptacles are provided in the lower ends of their rear sides with discharge slots 10.

85 The blanks are withdrawn one at a time from the receptacles 6 and moved through a shaping or forming means, by an annular series of carriers 11 which are supported for rotation beneath the blanks 7, and in a vertical plane located between the receptacles 6. The carriers 11 comprise plates 12 which are secured, as 13, to the outer side of the felly of a wheel 14. The plates 12 extend transversely of the wheel 14, and are provided at their rear edges with flanges 15. The wheel 14 travels in the direction indicated by the arrow of Figure 2, and during its rotation the car- 90

riers 11 withdraw blanks from the receptacles 6. The blanks 7 are withdrawn through the discharge slots 10 of the receptacles 6 by the flanges 15, and the blanks are held in the carriers by the flanges and by dogs 16, the flanges contacting with the rear edges and the dogs with the front edges of the blanks in the carriers. The dogs 16 are pivotally secured between their ends, as at 17, to the inner side of the felly of the wheel 14, and they are retractably held in active position by springs 18. The outer ends of the dogs 16 are, when the dogs are in active position, positioned at the front edges of the plates 12. The dogs 16 are in active position from the time the carriers receive the blanks until the articles are completed, and they are then moved into inactive position to permit the removal of the completed articles. The dogs 16 are retracted or moved into their inactive position against the tension of the springs 18 by a trip 19 which is of sector formation and supported from the frame in position to arrange its arcuate edge in the path of the inner ends of the dogs 16.

The wheel 14 is fixed to a shaft 20 which is journaled in bearings 21 carried by the frame bars 3. The felly 22 and the hub 23 of the wheel 14 are axially offset, and these parts are connected together by spokes 24 of the form shown in Figure 1. The trip 19 is supported concentrically with respect to the wheel 14 by a bracket 25 fixed, as at 25a, to the cross bar 4.

The means by which the blanks are bent or shaped to provide the comb honey sections comprise rods 26 and 27 and a rod 28. The rods 26 and 27 are of substantially semi-circular formation, and are arranged at opposite sides of the series of carriers 11 and eccentrically to the axis of rotation thereof. The rods 26 and 27 extend from points at and near the top of the path of movement of the carriers to points forwardly of and below the bottom of said path. They are fixed at their upper ends, as at 29, to a bar 30 which is in turn fixed, as at 31, to the lower ends of the front sides of the receptacles 6. The upper portions 26a and 27a of the rods 26 and 27 converge downwardly and rearwardly, and the lower portions 26b and 27b of the rods are substantially parallel. The rod 28 has an upper portion 28a which is substantially horizontal, and is fixed to one of the rear side bars 2. The rod 28 has a lower curved portion 28b which is arranged eccentrically to and in a plane centrally between the rod portions 26b and 27b, and is fixed at its lower end, as at 32, to the cross bar 4. The rod 28 also has an intermediate portion 28c which curves downwardly and rearwardly from a point near the lower end of the rod portion 26a to a point rearwardly of and centrally between the rod portions 26b and 27b.

The relative arrangement of the rod por-

tions 26a and 27a and their arrangement with respect to the path of travel of the series of carriers 11, are such that each blank will, during the first phase of its movement, after being withdrawn from the receptacles 6, contact with such portions and be moved downwardly and forwardly with respect to and between the same, with the result that the blank will be bent into the form shown at the rear of Figure 2 and in Figure 11. In these figures, 7a designates the bottom, 7b and 7c the sides and 7d the top of the partly formed sections. The bottom 7a is secured in its carrier 11, the sides 7b and 7c are positioned between and in contact with the rod portions 26a and 27a, and the top 7d extends rearwardly beyond said rod portions. During the next phase of the movement of the partly formed blanks, the top 7d thereof will contact with the rod portion 28c and the upper part of the rod portion 28b and be moved downwardly and forwardly with respect thereto, with the result that the top will be bent or moved in a direction to carry its free end toward the free end of the side 7b. During the next phase of the movement of the partly formed section, the sides 7b and 7c move between and in contact with the rod portions 26b and 27b and the top 7d moves in contact with the upper side of the rod portion 28b and is moved further in the direction of the free end of the side 7b. During the next phase of the movement of the partly formed section, it will be moved between the rollers 33 and 34 which are rotatably supported by brackets 35 and 36, respectively, carried by the frame bar 4.

The roller 33 contacts with the side 7c, and the roller 34 which is grooved, receives the dove-tail ends of the side 7b and top 7d and brings about an interlocking engagement of said ends.

To prevent any distortion of the partly formed section, and to hold its sides 7b and 7c against lateral separation, while it is being moved between the rollers 33 and 34, arms 37 and 38 are carried by the wheel 14 for engagement with the rear side of the section immediately before it starts to pass between the rollers 33 and 34. The arms 37 and 38 are arranged at opposite sides of the wheel 14 and are fixed to levers 39 and 39a which are in turn fixed to a shaft 40 journaled at the inner side of the periphery in the wheel. Immediately after the partly formed section enters between the rollers 33 and 34, one of the levers 39 comes in contact with a roller 41 journaled on the bracket 25, with the result that the arms 37 and 38 are moved into contact with the rear side of the partly formed section. The arm 37 is provided at its free end with a member 37a which contacts with the side 7b and holds it against outward displacement. After the section passes from between the rollers 33

and 34 the lever 39 passes beyond the roller 41, and during the next phase of the movement of the section, the dog 16 of the carrier in which the section is supported contacts 5 with the trip 19 and is thereby released. The dog 16 is held in this position by the trip 19 until after the carrier engages with another blank and is about to withdraw it from the receptacles 6. The dog 16 then passes beyond the trip 19 and is moved by its spring 18 into contact with the blank.

A lever 42 which is pivoted between its ends, as at 43, to the rear side of one of the receptacles 6, contacts with the outer side of 15 the felly of the wheel 14 in rear of the blanks 7 and serves to prevent the withdrawal of more than one of the blanks from the receptacles at one time. The lever 42 is 20 yieldingly held in contact with the felly of the wheel 14 by a spring 44.

The top and bottom starters of foundation comb, which is shown in Figure 11 and designated 7e and 7f, respectively, are cut from blanks 45 and 46, respectively, and applied 25 to the blanks 7 immediately after the blanks 7 are withdrawn from the receptacles 6 by the carriers 11. The blanks 45 and 46 are carried by rollers 47 which are rotatably mounted upon the shaft 48 arranged at a 30 point above and rearwardly of the receptacles 6. The shaft 48 is fixed to the upper end of a bar 49 which is arranged between the frame bars 3 and fixed to the cross bar 5. The blanks 45 and 46 rest upon plates 50 as 35 they are unwound from the spools 47. The plates 50 extend upwardly and rearwardly from the cross bar 5 which is provided with slots 51 for the reception of the blanks 45 and 46. Toothed wheels 52 which are fixed 40 to shafts 53 and contact with the upper sides of the blanks 45 and 46, serve to feed the blanks downwardly through the slots 51. The shafts 53 are journaled in bearings 54 carried by the side pieces 55 of the plates 50. 45 Ratchet wheels 56 are fixed to the shafts 53 and are engaged by spring pressed dogs 57 carried by the upper ends of rods 58. The rods 58 are slidably mounted as in 59, in the frame bar 5, and are provided at their lower 50 ends with the yokes 60 which embrace cams 61 and are provided with slots 62 for the reception of the shaft 63.

The upper ends of the rods 58 are pivoted, as at 58a, to pawls 58b pivotally associated 55 with the ratchet wheels 56.

The cams 61 are each of the double type, and are fixed to the shaft 63. The shaft 63 is journaled in bearings 64 carried by the frame bars 3, and is driven at twice the speed 60 of the shaft 20. During the rotation of the shaft 63, the cams 61 and springs 65 arranged upon the rods 58 between the frame bar 5 and yokes 60, move the rods upwardly and downwardly for each half revolution of the shaft. 65 During the downward movement of the rods

58, the dogs 57 engage the ratchet wheels 56 and move the notched wheels 52 to effect the feeding of predetermined portions of the blanks 45 and 46 through the slots 51.

These portions of the blanks 45 and 46 are 70 cut off and attached to the blanks 7 immediately after the withdrawal of these blanks from the receptacles 6. The severed portions of the blank 45 constitute the top starters of foundation comb, and the several portions of the blank 46 constitutes bottom starters of foundation comb, and said starters 7e and 7f are applied to the blanks 7. The blank portions are severed by knives 67 which are pivoted, as at 68, to the front side of the frame 75 bar 5. Levers 69 are pivotally connected at their lower ends, as at 70, to the bar 49, and have their upper free ends arranged in openings 71 formed in the knives 67. Cams 72 carried by the shaft 63 and working against 80 the upper sides of the levers 69, and leaf springs 73 fixed to the under side of the frame 85 bar 5 and contacting with the under sides of the levers, function to operate the levers in a manner to sever the required length from 90 the blanks 45 and 46. The knives are moved upwardly by the springs 73 to effect the severing of the required length of the blanks 45 and 46, and then are moved downwardly by 95 the cams 72 and held in a lowered position until after the passage of the required length of the blanks through the slots 51.

Hubs 74 each carrying a pair of oppositely extending arms 75, are fixed to the shaft 63. A pair of the arms 75 contacts with the under 100 sides of the projected lower ends of the blanks 45 and 46 immediately before said portions are severed from the remaining portions of the blanks. As soon as the arms contact with said blank portions, jaws 76 contact 105 with the upper sides of said portions and clamp said portions between themselves and the arms.

The severed portions of the blanks 45 and 46 are then carried by the arms to and have 110 certain of their edges wiped across a hot plate 77, and are thereafter carried by the arms to position said edges thereof in contact with the blanks 7 as the latter are withdrawn from the receptacles 6.

The free ends of the arms 75 and the jaws 76 are broad and flat to permit the severed portions of the blanks 45 and 46 to be held firmly until applied to the blanks 7. The jaws 76 are pivoted, as at 76a, to the arms 75, 120 and are held in active or clamping position with respect to the arms by coil springs 78. The jaws 76 are held in active position with respect to the arms 75 against the tension of the springs 78, until the arms are in position 125 to engage the blank portions by wipers 79 carried thereby and trips 80 carried by sleeves 81 which are fixed, as at 82, to the frame bars 3 and through which the shaft 63 extends. The plate 77 may be heated by steam, elec- 130

tricity or in any other suitable manner. Those edges of the severed portions of the blanks 45 and 46 that contact with this plate and are positioned in contact with the blanks 57, are melted sufficiently to cause them to adhere to the blanks 7, and as soon as said portions are secured to the blanks 7 the jaws 76 are opened by the contact of the wipers 79 with the trips 80.

10 A gear 83 is fixed to the shaft 20, and a gear 84 is fixed to the shaft 63, the former being twice the diameter of the latter. Gears 85 and 86 of the same diameter and meshing with each other and with the gears 83 and 84, 15 are mounted upon stub shafts 87 and 88 which are journaled upon one of the frame bars 3 between the shafts 20—63. A handle 89 for operating the machine is fixed to the top shaft 88. If desired, the handle 89 may be 20 omitted and any suitable motor which may be connected to the shaft 88 for the purpose of operating the machine.

While I have described the principle of the operation of the invention, together with the structure that I now consider to be the best embodiment thereof, I desire to have it understood that the structure shown is merely illustrative and that such changes may be made as desired as are within the scope of 25 the invention and claimed.

Having thus described the invention, what I claim is:

1. A machine for forming articles from blanks having ends adapted to be interlocked, 35 comprising a magazine for the blanks, means for bending the blanks, means for withdrawing the blanks from the magazine and subjecting them to the action of the bending means, and means for interlocking the ends 40 of the bent blanks.

2. A machine for forming articles from blanks having ends adapted to be interlocked, comprising a magazine for the blanks, means for bending the blanks, an annular series of 45 carriers adapted to withdraw the blanks from the magazine and subject them to the action of the bending means, means for operating the carriers, and means for interlocking the ends of the bent blanks.

3. A machine for forming articles from blanks having ends adapted to be interlocked, comprising a magazine for the blanks, an annular series of carriers adapted to withdraw the blanks from the magazine during one 55 phase of their movement, blank bending means adapted to engage the blanks during another phase of their movement, means for interlocking the ends of the shaped blanks during another phase of their movement, 60 and means for rotating the carriers.

4. A machine for forming articles from blanks having ends adapted to be interlocked, comprising a magazine for the blanks, an annular series of carrier, means for rotating 65 the carriers, arcuate blank bending members

extending from the top to the bottom of the path of movement of the carriers, the members being arranged eccentrically to the axis of rotation of the carriers and having downwardly converging upper portions and parallel lower portions, another blank bending member having an arcuate lower portion arranged eccentrically to the lower portions of said first members, said other member having an upper portion inclining downwardly and inwardly from the lower end of the upper portion of one of said first members, and means arranged at the lower ends of said members for interlocking the ends of the blank.

5. A machine for forming articles from blanks having ends adapted to be interlocked, comprising a magazine for the blanks, means for bending the blanks, means for interlocking the ends of the shaped blanks, an annular series of carriers adapted to withdraw the blanks from the magazine and carry them through the bending and interlocking means, spring pressed dogs adapted to retain the blanks in the carriers during the passage of the blanks through the bending and interlocking means, and means adapted to retract the dogs after the passage of the completed article through the interlocking means and hold the dogs retracted until the carriers engage other blanks.

6. A machine for forming articles from blanks having ends adapted to be interlocked, comprising a magazine for the blanks, means for bending the blanks, means for interlocking the ends of the shaped blanks, an annular series of carriers adapted to withdraw the blanks from the magazine and carry them through the bending and interlocking means, spring pressed dogs adapted to retain the blanks in the carriers during the passage of the blanks through the bending and interlocking means, and means adapted to retract the dogs after the passage of the completed article through the interlocking means and hold the dogs retracted until the carriers engage other blanks, and means operable for movement into contact with the bent blanks for holding them against distortion during 115 their passage through the interlocking means.

7. A machine for forming articles from blanks having ends adapted to be interlocked, comprising a magazine for the blanks, means for bending the blanks, means for interlocking the ends of the bent blanks, an annular series of carriers adapted to withdraw the blanks from the magazine and carry them through the bending and interlocking means, means operable to engage the bent blanks immediately before their passage through the interlocking means, and means for moving said last means into engagement with the bent blanks and for releasing the same after 130

the passage of the blanks through the interlocking means.

8. A machine for forming articles from blanks having ends adapted to be interlocked, comprising a magazine for the blanks, means for bending the blanks, means for interlocking the ends of the bent blanks, carriers adapted to withdraw the blanks from the magazine and carry them through the bending and interlocking means, and means for holding the blanks in the carriers during their passage through the bending and interlocking means and adapted to release the blanks after their passage through the interlocking means.

9. A machine for forming comb honey sections from blanks having ends adapted to be interlocked, comprising a magazine for the blanks, means for bending the blanks, means for interlocking the ends of the bent blanks, means adapted to withdraw the blanks from the magazine and carry them through the bending and interlocking means, and means for applying top and bottom starters of foundation combs to the blanks during their withdrawal from the magazine and prior to their engagement with the bending means.

10. A machine for forming articles from blanks having ends adapted to be interlocked, comprising a magazine for the blanks, means for bending the blanks, means for interlocking the ends of the bent blanks, carriers adapted to withdraw the blanks from the magazine and carry them through the bending and interlocking means, a wheel supporting the carriers, arms pivotally mounted upon the wheel for movement into contact with the bent blanks prior to their passage through the interlocking means, and means for operating said arms and releasing them after the passage of the bent blanks through the interlocking means.

11. A machine for forming articles from blanks having ends adapted to be interlocked, comprising a magazine for the blanks, means for bending the blanks, means for interlocking the ends of the bent blanks and carriers adapted to withdraw the blanks from the magazine and carry them through the bending and interlocking means, said interlocking means embodying rollers of which one is grooved for the reception of the ends of the bent blanks.

12. A machine for forming and applying top and bottom starters to a comb honey section blank, comprising a support for the blank, means for supporting a substance from which the starters are cut, means for cutting the starters, a hot plate, and means for delivering the starters to said blank after passing certain of the edges of the starters over the hot plate.

13. A machine for forming and applying top and bottom starters to a comb honey sec-

tion blank, comprising a support for the blank, means for supporting a flat substance from which the starters are to be cut, means for cutting the starters, a hot plate, and means for delivering the starters to said blank after 70 passing certain of the edges of the starters over the hot plate, said last means comprising a shaft rotatably mounted, arms carried by the shaft, jaws pivoted to the arms and cooperating therewith to grip the starters, 75 means for holding the jaws open during a phase of the rotation of the arms, and means for closing the jaws to grip the starters and for holding the jaws closed until after the application of the starters to said blank. 80

14. A machine for forming and applying top and bottom starters to a comb honey section blank, comprising a support for the blank, means for supporting flat substances for top and bottom starters, means for severing portions of said substances, means for feeding said substances to the severing means, means for operating the severing means, and means for applying the severed portions of said substances to said blank, said severing 90 and operating means embodying pivoted knives, pivoted levers engaged with the knives, and means for moving the levers in opposite directions.

15. A machine for forming and applying top and bottom starters to a comb honey section blank, comprising a support for the blank, means for forming the starters, and means for heating certain edges of the starters and applying the starters to the blank with 100 the heated edges thereof in contact with the blank.

16. A machine for forming and applying top and bottom starters to a comb honey section blank, comprising a support for the blank, means for forming the starters, and means for heating certain edges of the starters, and means for applying the starters to said blank with the heated edges thereof in contact with the blank, said last means embodying pivoted arms, jaws pivoted to the arms, means for opening and closing the jaws, and a hot plate. 110

17. A machine for applying starters to comb honey section blanks, comprising a magazine for the blanks, means for withdrawing the blanks from the magazine one at a time, a heater, means for forming the starters, and means for presenting certain edges of the starters to the heater and thereafter applying the starters to the blanks with said edges thereof in contact with the blanks. 120

In testimony whereof I affix my signature.
WILLIAM D. RIDGWAY.
